OF TOLEDO, OHIO, A CORPORATION OF OHIO.

ELECTRIC WELDING-MACHINE.

1,098,550.

Specification of Letters Patent. Patented June 2, 1914.

Application filed November 27, 1911. Serial No. 662,704.

To all whom it may concern:

Be it known that I, FRANK E. BEAM, a citizen of the United States, and a resident of Toledo, in the county of Lucas and State of Ohio, have invented a certain new and useful Electric Welding-Machine; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to electric metal-working apparatus designed for use in welding, forging, upsetting, and other operations wherein the work is heated to the desired condition of plasticity for such purposes by the passage therethrough of an electric current.

20 The primary object of my invention is the provision of a machine for the manufacture of wire loops or rings of rectangular or other desired form for use in closing the open ends of bags filled with lime or other matter, such articles being slipped over the contracted end of a bag and then twisted to securely close the same. The machine is not 25 limited to the making of such articles, however, as it may be used for any purpose for which it is applicable.

25 The invention is fully described in the following specification, and while, in its broader aspect, it is capable of embodiment in numerous forms, a preferred embodiment thereof is illustrated in the accompanying drawings, in which,

30 Figure 1 is a side elevation of a machine embodying the invention with portions broken away, and the parts shown in wire feeding position. Fig. 2 is a top plan view thereof, with parts broken away. Fig. 3 is an enlarged vertical cross-section on the line 35 x, x in Fig. 1 with portions broken away. Fig. 4 is a similar section on the line y, y in Fig. 2. Fig. 5 is an enlarged side elevation of a portion of the machine with parts removed and broken away, and with the 40 parts in work welding position. Fig. 6 is an enlarged plan of the rear end portion of the machine with parts broken away and removed and with the parts shown in work welding position. Fig. 7 is an enlarged side 45 elevation of the work shaping parts, partly

in section, with a wire formed in U-shape. Fig. 8 is a similar view of such parts on a larger scale with the parts in work welding position and with portions broken away. Fig. 9 is an enlarged detail of the cams and 50 coating parts which move the forming blocks. Figs. 10 and 11 are side views of the cams controlling the movements of the mandrel and movable die carrying arm, respectively, and Fig. 12 is a view of the mandrel and associated parts in elevated position.

55 In the machine which I have illustrated as embodying my invention, 1 designates the base member thereof, 2, 2 opposing side standards, which rise therefrom, and 3 a frame part which also rises from such base in advance of said standards, and which will be hereinafter more fully described.

60 Each of the standards 2 is shown in the present instance as being provided with vertical slots or openings 4 in which upper and lower bearing-blocks 5 and 6 are slidingly mounted and spaced apart by posts or spacing members 7. The upper set of such bearing blocks are yieldingly held in lowered position by coiled compression springs 8, which are disposed within said slots and have their lower ends thrust against the respective bearing blocks 5 and their upper ends thrust 65 against adjusting screws 9 which are threaded through cap strips 10, one of which is secured to the upper end of each standard 2 over the slot therein. Shafts 11 and 12 are mounted in the respective sets of bearing blocks 5 and 6, and respectively carry gears 13 and 14 without said standards. These gears are of like size and mesh together so 70 as to drive the shafts 11 and 12 in unison, and the gear 14 has a small drive gear 15 meshing therewith and carried by a shaft 16, which is journaled in suitable bearing standards 17 rising from the base 1, and carries a set of fast and loose belt pulleys 18. Each of the shafts 11 and 12 carries a segmental 75 wire feeding member 19, and these members are adapted to coöperate during predetermined portions of their revolutions to feed a predetermined length of a wire a to the shaping and welding parts.

80 The wire a , to the rear of its point of entrance between the feed members 19-19, passes through any suitable form of straightener mechanism 20, and after passing 85 between said members is fed forward 90 to the shaping and welding parts.

95

105

100

105

110

through a registering feed opening 21 in a stationary frame part 22, which is fixed intermediate the standards 2—2, see Figs. 1, 3 and 5, and thence over the top of the frame part 3, as hereinafter described.

A wire severing knife 23 is suitably carried for vertical reciprocatory movements by the standards 2 at their upper forward edges and is intermittently reciprocated to sever a fed wire section *b* and then to recede from wire severing position by the action of a pair of levers 24, one of which is mounted on a pivot 25 at the outer side of each standard 2 adjacent its upper end and has one end in forked engagement with a stud 26 projecting from the associated side edge of the knife 23 adjacent its upper end, and has its rear end positioned to be acted on by a wiper or cam wheel 27, which is mounted on the associated end of the shaft 11. The striking or moving of the levers 24 by the cams 27 is timed to take place at approximately the end of a feeding operation of the feed members 19 so that the wire *a* will be at rest when the severing takes place. A coiled expansion spring 28 acts on each lever 24 to normally retain the knife 23 in raised or retracted position.

The frame part 3 is provided at its top with a table 3^a which is divided longitudinally thereof or lengthwise of the machine into two sections by a vertical incut or opening 3^b in the upper portion of the frame, as shown. The table 3^a of the frame has its top surface longitudinally grooved or otherwise suitably formed at each side of the opening 3^b to form ways in which wire shaping blocks 29—29^a are mounted for reciprocal movements. These blocks have their upper surfaces in substantially the plane of feed of the wire *a* and are provided with longitudinally extending surface grooves 30, which extend at their inner ends around the inner or adjacent ends of the blocks and thence under the blocks lengthwise thereof for a short distance, as best shown in Figs. 4, 5 and 8, with the portions of such grooves which are provided on the upper surfaces of the respective blocks disposed in register with the wire feed opening 21 in the guide part 22 to permit the wire *a* to feed across both of such blocks within said grooves. The means employed for imparting the respective reciprocal movements to the blocks 29 and 29^a will be hereinafter described.

A wire forming mandrel 31, which may be of any desired form in cross-section, is mounted for vertical reciprocal movements in the opening 3^b of the frame 3, and is guided in its movements by an arm 31^a, which projects downward from one end thereof and works in guides 31^b secured to the frame 3 adjacent the side edges of the opening 3^b. A plunger 32 works upward

through the frame 3 into the opening 3^b beneath the mandrel 31 and has a stem 32^a projecting downward from its lower end and working through a registering opening in the base 1 and a subjacent guide part 33. A coiled compression spring 34 is mounted on the stem 32^a, and has its opposite ends thrust against the guide 33 and a collar or shoulder 35 on the stem to tend to normally move the plunger to elevated position. A stop member 32^b on the lower end of the stem 32^a coacts with the guide 33 to limit the upward movement of the plunger so that a free wire-feeding space will be provided between the plunger and mandrel when both are in elevated positions, as shown in Figs. 1 and 12.

The reciprocal movements of the mandrel 31 are controlled by a revoluble cam 36 working between rollers 37 and 37^a carried by spindles projecting from the outer side of the mandrel arm 31^a, as best shown in Fig. 12. The cam 36 is carried by a shaft 38, which is mounted in bearing standards 39, 39 rising from the base 1. A gear 40 is mounted on the shaft 38 intermediate the bearings 39—39 and is the same size as the gear 14 and driven in unison therewith by the drive-gear 15 with which it meshes to cause the cam 36 and feed members 19—19 to revolve at the same speed. The shape of the cam 36 is such that the mandrel 31 will stand in raised position during the feeding action of the wire *a* to permit such wire to be fed thereunder and over the plunger 32 and forming blocks 29—29^a, and, upon a severing of the wire, will cause a lowering of the mandrel within the frame opening 3^b to draw the severed wire section *b* into U-shape within such opening, as shown in Fig. 7. After the terminals of the section *b* have been bent over the top of the mandrel and the welding together of the same performed, as hereinafter described, the cam will act to quickly raise the mandrel to its elevated position to permit the feeding of another section of wire thereunder. Upon a lowering of the mandrel from its elevated position the central portion of the wire section *b* is first lowered into contact with the upper end of the plunger 32, so that the mandrel and plunger coöperate to firmly grip the wire to prevent endwise movements thereof during the forming operation, the plunger being forced downward by the mandrel upon the continued lowering thereof, as is apparent.

When the mandrel 31 is in lowered position within the frame opening 3^b the forming blocks 29—29^a are moved toward each other over the adjacent portions of the mandrel top to effect a bending of the terminal ends of the wire section *b* thereover in lapping relation, as indicated in Fig. 8, the block 29 preferably moving slightly in advance of the other block to cause the wire

terminal acted on thereby to be first folded over the mandrel so that the end of the other wire terminal will lap over its end.

The blocks 29—29^a have forked portions 5 41 working down through registering slots in the respective frame parts 3^a for the upper ends of the respective actuating rock-arms 42 and 43 to project into, as best shown in Fig. 5. These arms are carried by shafts 10 42^a and 43^a, respectively, which are journaled in the frame part 3 and have arms 42^b and 43^b projecting downwardly from their outer ends and attached to one end of the respective bars 44 and 45, the opposite ends of which 15 are mounted for relative longitudinal reciprocal movements upon the associated end of the shaft 12, being slotted at such ends for that purpose. Opposed reciprocal movements are imparted respectively to the bars 20 44 and 45 by the action thereon of cams 46 and 47 fixed to the shaft 12, the former of which acts on a roller 48 projecting laterally from the bar 44, while the latter thereof acts on a roller 49 projecting laterally from the 25 arm 45, as best shown in Fig. 9. The cams 46 and 47 and the rollers with which they respectively coact are so relatively arranged that they will impart opposite oscillatory movements in unison to the levers 42 and 43 30 when the mandrel 31 is in lowered position to move the forming blocks 29 and 29^a toward each other to fold the end portions of the looped wire section *b* over the mandrel 31 with their terminalslapping each other 35 as shown in Figs. 5 and 8. As soon as the ends of a wire section *b* have been bent over the mandrel the cams permit a recession of the forming blocks 29 and 29^a under the influence of the spring 45^a, from over the man- 40 drel 31 to permit the mandrel to rise when the welding operation has been completed, as hereinafter described.

Pivoted to an arm rising from the rear end of the table 3^a, as at 50, is a forwardly 45 projecting forked arm 51 the lower furcation of which, at the under side of its free end, carries a welding die or electrode 52, which, when lowered from the normal position shown in Fig. 1, and the mandrel 31 is in 50 its lowered position, coacts with a die or electrode 53 mounted in the top of the mandrel 31 to clamp and electrically weld the lapped ends of a wire section *b* when the welding circuit is closed for such purpose, 55 as best shown in Figs. 5 and 8. The die 52 is connected through a hinged or jointed lead 54 with one terminal of the secondary 55 of a transformer 56, of any suitable construction, while the die 53 has connection- 60 through a hinged or jointed lead 57 with the other terminal of the secondary 55 to close a circuit through the transformer when the dies 52 and 53 are electrically connected, as is well understood in the art.

65 A circuit-closer, having the parts 58 and

59, is disposed in circuit with the primary 60 of the transformer and a source of electrical supply through the wires 61 and 62, and the part 59 is moved into contact with the part 58 to close the primary circuit at a 70 predetermined point in each rotation of the shaft 38, or in each cycle of operations of the machine, by contact therewith of a lug 63 (see Figs. 1 and 4) which is provided on one side of a cam 64 carried by the shaft 38. 75

An arm 65 projects downward and forward from the pivotal end of the forked arm 51 and carries a roller at its free end in peripheral contact with the cam 64 to control the movements of the arm 51, said cam being of suitable form to effect a lowering of the arm at approximately the time and speed of lowering of the mandrel 31, whereby the die 52 is caused to coact with the mandrel die 53 to grip and weld the work when the mandrel is at the lowest point of its movement, after which the arm 51 is quickly raised to the normal position shown in Fig. 1. While the cam 64 co-operates with the arm 65 to control the lowering movements 80 of the die 52 a coiled contraction spring 66 coacts with the opposite end of such arm to return it and the arm 51 to raised or normal position.

A spring finger 67 is secured to the inner 85 end portion of the arm 51 to the upper side thereof and projects rearwardly over the free end thereof and thence downward to the rear of the die 52 in position for its free end to bear downward upon the rear one of the folded-over ends of the wire section *b* when the die is in work clamping or welding position. The free end of the spring finger 67 normally projects slightly below the plane of the lower end of the die 52 100 to adapt it to coact with the end portion of the wire section *b*, which is first folded over upon the mandrel 31, to hold such end steady while the other end is lapped thereover and clamped thereto preparatory to welding. To prevent a relative lateral movement of the wire ends when engaged by the die 52 and finger 67 the wire coacting surfaces of such members are notched to seat over the respective wire ends, as indicated. 105 A spring 68 is fixed to the arm 51 without the inner end of the spring finger 67 and projects rearward over such finger to co-operate with the spring action thereof to resist a springing of the finger when in 110 clamping engagement with the work. 115

When the mandrel 31 has been raised to its elevated position with a welded wire section *b* therearound, a work ejecting member 69 is moved to coact with and eject the welded wire from one end of the mandrel. The member 69 is shown as being angled in U-shape, to adapt it to extend partially around the mandrel when the latter is elevated, and is attached to the rod 70, which 120 125

is mounted above the elevated position of the mandrel for reciprocatory movements transversely of the machine. The rod 70 has one end guided for reciprocal movements by an arm 71 projecting forward from the upper end portion of one of the standards 2, and has its opposite end pivotally attached to an end of the control lever 72, which lever projects forward and 5 downward therefrom and is fulcrumed to studs 73 projecting from the outer side of the associated standard 2. A cam 74 which is mounted on the shaft 12 adjacent to the gear 14 acts upon a roller carried at the 10 lower rear end of the lever 72 to control the ejecting movements of the ejecting member 69. A coiled contraction spring 75 connects the forward end portion of the lever 72 to the arm 71 and acts on the lever to yield- 15 ily retain its lower end in engagement with the cam 74.

The operation of the machine is as follows: In starting a cycle of operations of the machine the mandrel 31 and die carrying arm 51 stand in the elevated positions 20 shown in Fig. 1 and the wire feed members 19 act to feed a length of wire *a* across the tops of the forming blocks 29 and 29^a and under the mandrel 31. Approximately 25 at the time of stopping of the feed of the wire *a*, by reason of the feed members 19, 19 moving from engagement therewith, the cams 27 act on the levers 24 to impart a wire severing movement to the knife 23. When 30 the section *b* has been severed from the wire thread the cam 36 on the shaft 38 has moved a sufficient distance for its neutral portion to pass from under the roll 37, the cam then 35 acting to lower the mandrel 31 to effect a gripping of the wire section between the mandrel and yieldable plunger 32 and a drawing of the wire section into U-shape within the frame opening 3^b, as shown in Fig. 7. The cams 46 and 47, which are carried by 40 the shaft 12, now act upon the bars 44 and 45, attached to the levers 42^b and 43^b, respectively, to impart inward movements to the forming blocks 29 and 29^a to bend the upwardly projecting end portions of the 45 wire section *b* over the top of the mandrel 31, the wire end which is acted upon by the block 29 being first folded upon the mandrel 31 to permit the terminal portion of the other end to lap thereover, as best 50 shown in Fig. 8. By the time the ends of the wire section *b* have been lapped over each other in this manner the arm 51 has lowered sufficiently, by the action of the cam 64 on the arm 65, to cause the free end of the 55 spring-finger 67 to first engage the rear one of the section ends to hold it firmly to the mandrel, and immediately after such engagement of the spring-finger 67 with the wire section the die descends upon the lapping 60 portions of the wire ends to clamp 65

them together. As soon as the die 52 has descended into wire clamping position the boss 63 on the cam 64 will have moved into contact with the yielding part 59 of the circuit closer 58, 59 to move said parts into contact to close the welding circuit. The coaction of the boss 63 and circuit closer part is of sufficient duration to effect the proper welding of the ends of the wire section *b* after which the cam 64 acts upon the arm 65 to raise the die carrying arm 51, and the cam 36 acts upon the roller 37 to raise the mandrel to its elevated position, thus completing a cycle of operations of the machine. When such cycle of operations is 70 completed the wire feed members 19, 19 will have again moved into wire feeding position and effect a feeding of another length of wire across the forming blocks 29, 29^a and under the mandrel, and the severing, forming and welding of the same will 75 be then accomplished as above described. During the feeding of a wire section the cam 74 permits a movement of the lever 72, actuated by the spring 75 to move the ejector 80 finger 69 to effect an ejection of a welded wire section from the mandrel.

It is apparent that I have provided a simple and efficient machine which is automatically operable to intermittently feed a 85 length of wire to the forming parts, then to sever the fed section and act upon it to form it into rectangular or other desired shape, depending upon the form of the mandrel, after which the ends of the wire section are 90 welded together and the wire then ejected from the machine.

I wish it understood that my invention is not limited to any specific construction or arrangement of the parts except in so far as 105 such limitations are specified in the claims.

Having thus described my invention, what I claim as new and desire to secure by Letters Patent, is,—

1. In an electric welding machine, a movable work shaping member having a part forming an electrode, and mechanism having an automatically movable part for coöperating with said electrode at a predetermined point in a movement of said member to electrically weld an article carried thereby.

2. In an electric welding machine, a reciprocal work shaping member having a part forming an electrode, and mechanism having an electrode which is automatically movable to coöperate with the electrode of said member at a predetermined point in its movement to weld an article carried thereby.

3. In an electric welding machine, a reciprocal mandrel, means controlling the reciprocal movements of the mandrel, means operable to coöperate with the mandrel when in one position of its movement to shape work, and an electrode automatically mov-

able to coöperate with a part of the mandrel at a predetermined point in the movement thereof to weld work.

4. In an electric welding machine, a reciprocal mandrel yieldingly movable in one direction, means controlling the movements of said mandrel, cam controlled means for coöperating with the mandrel to shape work, and a set of electrodes automatically operable to effect a welding of the work when shaped.

5. In an electric welding machine, a set of relatively movable electrodes, an arm carrying one of said electrodes and operable to impart predetermined movements to the electrode, and a spring finger carried by said arm and operable to engage and hold a portion of the work without the point of weld prior to a clamping of the work by the electrodes.

20 6. In an electric welding machine, a mandrel, an electrode carried by the mandrel, means operable to coöperate with the mandrel to shape work therearound and to lap its ends over said electrode, and means operable to first clamp the work and then to electrically weld the lapping ends thereof.

7. In an electric welding machine, work shaping mechanism operable to shape and lap the ends of a piece of work over a mandrel part in laterally abutting relation, means operable to electrically weld the lapping work ends, and means automatically operable to engage and hold a portion of the work prior to and during the welding operation.

40 8. In an electric welding machine, a mandrel, means for shaping a piece of work about said mandrel and lapping one end thereof over the other, means automatically operable to weld the lapped ends of the work, and a clamping part movable to engage and hold one of the work ends stationary prior to and during the welding operation.

45 9. In an electric welding machine, work shaping mechanism operable to shape and lap the ends of a piece of work over a mandrel part in laterally abutting relation, means operable to electrically weld the lapping work ends, and means automatically operable to engage an end portion of the work without the point of weld and hold it to the mandrel during the welding operation.

55 10. In an electric welding machine, work shaping mechanism operable to shape and lap the ends of a piece of work over a mandrel part in position to laterally abut one without the other, means automatically operable to engage the innermost end portion of the work without the point of weld and hold it to the mandrel, and means operable to clamp the outermost work end to the other end and to coöperate with a part of

said mandrel to electrically weld the work ends.

11. In an electric welding machine, a reciprocating work shaping mandrel having a part thereof forming an electrode, an electrode for coöperating with said mandrel electrode to weld together the interposed lapped work ends.

70 12. In an electric welding machine, a work shaping mandrel having a part thereof forming an electrode, and means for coöperating with said mandrel part to clamp interposed lapping work ends together, and means movable to hold a portion of the work without the point of weld prior to the clamping action of the welding means.

75 13. In an electric welding machine, a mandrel having a part forming an electrode, means for folding work portions in opposite directions over the mandrel with their adjacent ends lapping, means for clamping one of the work portions to the mandrel, and an electrode automatically operable to coöperate with the electrode of said mandrel to clamp the work ends together and weld the same subsequent to the clamping action of said clamping means.

80 14. An electric welding machine having relatively movable electrodes and a yieldingly movable finger disposed without the work-clamping point of said electrodes and insulated therefrom, said finger being operable upon a relative clamping movement of the electrode to engage a portion of the work and hold it stationary during the welding operation.

85 15. In an electric welding machine, work shaping mechanism having a movable mandrel part about which work is shaped and an electrode operable at a predetermined point in the movement of said mandrel to move between parts of the shaping mechanism to weld lapping portions of the work.

105 16. In an electric welding machine, a movable work shaping mandrel having a part forming an electrode, cam means controlling the movements of said mandrel, and mechanism operable by said cam means and having an electrode for coöperating with said mandrel at a predetermined point in its movement to weld together the ends of work shaped by the mandrel.

110 17. In an electric welding machine, a reciprocally movable work-shaping mandrel, an electrode for coöperating with a part of said mandrel to weld work carried thereby, and means having parts in common for moving the mandrel to shape work and the electrode to coöperate with a part of the mandrel at a predetermined point in its movement to weld the work.

120 18. In an electric welding machine, a reciprocally movable work-shaping mandrel, a cam operable to impart movements to the mandrel, an electrode for coöperating with

a part of the mandrel to weld work, and means actuated by said cam to move the electrode to clamp work to the mandrel at a predetermined point in the movement of the mandrel.

19. In an electric welding machine, a reciprocally movable work-shaping mandrel, a cam operable to impart movements to the mandrel, an oscillatory electrode, and means operated by said cam for moving the electrode to coöperate with a part of the mandrel to clamp work at a predetermined point in a movement of the mandrel.

20. In an electric welding machine, a reciprocally movable work-shaping mandrel, a cam operable to impart movements to said mandrel, an oscillatory electrode, means

movable by said cam for moving said electrode to coöperate with a part of the mandrel to clamp work at a predetermined point 20 in the movement of the mandrel, and a work clamping member yieldingly movable with the electrode and adapted to clamp work to the mandrel without the point of weld and prior to the clamping action of said electrode and mandrel part. 25

In testimony whereof, I have hereunto signed my name to this specification in the presence of two subscribing witnesses.

FRANK E. BEAM.
